UNITED STATES PATENT OFFICE.

EDWARD M. S. THOMESSEN, OF CHICAGO, ILLINOIS.

FOLDING METAL BED.

1,140,212.

Specification of Letters Patent. Patented May 18, 1915.

Application filed January 3, 1914. Serial No. 810,157.

To all whom it may concern:

Be it known that I, EDWARD M. S. THOMESSEN, a subject of the King of Norway, residing at Chicago, in the county of Cook and State of Illinois, have invented certain new and useful Improvements in Folding Metal Beds, of which the following is a specification.

My invention relates to improvements in folding beds, preferably formed of metal, while the same may be formed of any other suitable material.

An important object of the invention is to provide a bed of the above-mentioned character, which is simple in construction, inexpensive to manufacture, convenient in use, and will occupy when folded the minimum space for shipment or exhibition.

Other objects and advantages of the invention will be apparent during the course of the following description.

Figure 1 is a plan view of the bed with parts in section. Fig. 2 is a longitudinal sectional view taken on the line 2—2 of Fig. 1. Fig. 3 is a transverse sectional view taken on the line 3—3 of Fig. 1. Fig. 4 is a similar view taken on line 4—4 of Fig. 1. Fig. 5 is a horizontal section on line 5—5 of Fig. 3. Fig. 6 is a side elevation showing the bed folded and Fig. 7 is a detail side elevation of a foot removed.

My improved bed structure comprises a head member 1, and a foot member 2 preferably formed of metal, but any suitable material may be employed. Each head and foot member comprises upstanding preferably tubular standards 2^a, connected near and spaced from their lower ends with preferably tubular horizontal bars or elements 2^b, as shown. The lower end of each of the tubular standards 2^a, is preferably provided with a foot, designated as a whole by the numeral 3. Each foot 3 (see Fig. 7) comprises a preferably tubular body portion 4, to the lower end of which is suitably secured a caster 5', as shown. The upper end of the tubular body portion 4 receives a connecting plug 5, which enters the lower end of the tubular standard 2^a, to securely preferably detachably connect the foot thereto, as is obvious.

The members 1 and 2 are connected by substantially rectangular frames A and B. These frames or frame-sections A and B, are identical, each comprising longitudinal rails 6, which are preferably inverted L-shaped in cross section and connected at their outer ends by transverse horizontal bars 7, also formed inverted L-shaped in cross section. The inner contiguous ends of the longitudinal rails 6 are disposed in end to end relation as shown, and connected by hinge means to be described; the rails 6 of frame B being movable into the rails 6 of the frame A, which may be accomplished by swinging the vertical webs of rails 6 of frame B in to rails 6 of the frame A. This hinge means comprises a connecting member 8, arranged within each of the rails 6 of the frame B, and rigidly secured thereto by means of bolts or rivets 9, having their heads preferably countersunk, as shown. As more clearly shown in Fig. 4, each connecting member 8 is preferably inverted U-shaped in cross-section with one end extending into the rail 6 of the frame A. Passing through apertures in the connecting members 8 and in the vertical webs of rails 6 of frame A is a transverse rod 10, the ends of which are flattened to retain the same in place. It is thus seen that a hinged joint is obtained between the inner ends of the frames A and B, whereby such inner ends may be readily swung upwardly but not downwardly below the horizontal position of the rails 6. Arranged within each of the connected members 8 is a spacing sleeve or ring 11 preventing lateral bending of the sides of the connecting member and consequently perceptible lateral movement of one rail 6 with relation to the adjacent rail 6. The intermediate portion of the rod 10 is bent downwardly or depressed, and carries a spacing tube 12, correspondingly depressed or bent, and preferably loosely mounted thereon. The ends of this tube engage the connecting members 8, and together with the spacing sleeves or rings 11, serve to prevent improper relative lateral movement of the rails 6, such as bulging, or contracting laterally. The transverse bars or members 7 of the frames A and B are pivotally

connected with the bars or members 2^b to swing in a substantially vertical plane, by means of hinges 13, as shown.

Means are provided to lock the frames A and B in their horizontal position, comprising eyes 14 (see Fig. 5) projecting through openings 15 formed in the standards 2^a.

The numeral 16 designates guide lugs carried by the members 7, receiving reciprocating bolts 17, to pass into and out of the eyes 14. These bolts 17 have their inner ends bent to afford lateral extensions 18, apertured to receive a rod 19. Surrounding the rod 19 is a compressible coil spring 20, serving to urge the bolts 17 outwardly, as shown.

The numeral 21 designates a bed bottom, preferably formed of an open metal fabric, attached to the rails 6 and bars or members 7 by refractive coil springs 22. The springs 22 are under suitable tension, when the rails 6 occupy their horizontal position, to retain the intermedial or central portion of the bed-bottom taut.

25 In the use of the bed structure, when it is desired to fold up the same, the bolts 17 are withdrawn from the eyes 14, whereby the inner ends of the frames A and B may be swung upwardly, the rails 6 of the frame B 30 passing into the rails 6 of the frame A, as more clearly shown in Fig. 6. The members 1 and 2 then lie flat against the frames A and B. When thus folded, the bed-bottom 21 is also folded about the tube 12, to 35 be supported thereby, whereby the entire bed structure will occupy the least space.

It is obvious that the frames A and B may be readily swung to the horizontal, and again locked in such position by means of 40 the bolts 17 and associated elements.

It is to be understood that the form of my invention is to be taken as a preferred embodiment of the same, and that various changes in the shape, size and arrangement 45 of parts, without departing from the spirit of the same or the scope of the subjoined claims.

Having described the invention what is claimed, is:—

50 1. A bed comprising head and foot members; cross bars hinged to the head and foot members to turn upon their longitudinal axes; lugs secured to the inner sides of the head and foot members and arranged in 55 proximity to the cross bars; movable bolts secured to the cross bars and movable into and out of engagement with the lugs; side rails connected with the cross bars, comprising sections which are pivotally connected; 60 and a bed bottom co-operating with the cross bars.

2. A bed comprising head and foot members, cross bars hinged to the head and foot members, eyes carried by the head and foot

members, spring pressed bolts carried by 65 the cross bars and engageable with the eyes, side rails connected with the cross bars and comprising sections pivotally connected together, and a bed bottom connected with the cross bars. 70

3. A bed comprising head and foot members, cross bars hingedly connected with the head and foot members, eyes carried by the head and foot members and adapted to pass through the cross bars, bolts slidably mounted upon the cross bars and having inwardly disposed extremities at their inner ends, springs interposed between the extremities of the adjacent bolts and being under tension with a tendency to force the bolts away 80 from each other and through the said eyes, side rails connected with the cross bars and composed of sections hingedly connected together and a spring fabric connected with the side rails and cross bars. 85

4. A bed structure, comprising head and foot members, rails having their outer ends permanently pivotally connected with the head and foot members and adapted to swing in a substantially vertical plane, a 90 bed-bottom, resilient means connecting the bed-bottom with the head and foot members, and a transverse member serving to permanently pivotally connect the inner ends of the rails and having its intermediate portion depressed to be spaced a substantial distance below the bed-bottom when said bed-bottom is horizontally arranged and to engage the bed-bottom when the rails are swung upwardly in the folding operation of the bed with all the parts thereof intact. 95

5. A bed structure, comprising head and foot members, rails pivotally connected therewith, a bed bottom, means connecting the bed bottom with the rails, a transverse rod serving to pivotally connect the inner ends of the rails and bent downwardly between the rails and arranged below the bed bottom, and a spacing tube arranged upon 110 the rod and serving as means to prevent improper relative lateral movement of the rails. 105

6. A bed structure, comprising head and foot portions, rails having their outer ends pivoted to the head and foot portions, channeled connecting members secured to corresponding rails and extending across adjacent ends of the other rails, a transverse rod passing through the inner ends of the said 115 other rails and the connecting members, spacing rings carried by the rod and arranged within the channeled connecting members, a spacing tube mounted upon the rod and engaging the connecting members, 120 and a bed-bottom secured to the rails. 125

7. A bed, comprising an end member, a transverse member hinged to the end mem-

ber and provided with transverse openings, rails connected with the transverse member, eyes secured to the end member and adapted to pass through the openings, and fastening means coöperating with said eyes operable intermediate the ends of the transverse member.

In testimony whereof I affix my signature in presence of two witnesses.

EDVARD M. S. THOMESEN.
